UNITED STATES PATENT OFFICE.

SIDNEY EALES HALES, OF BLACKHEATH, LONDON, ENGLAND.

PUMP.

Application filed March 28, 1922. Serial No. 547,426.

To all whom it may concern:

Be it known that I, SIDNEY EALES HALES, a subject of the King of Great Britain, residing at 101 Westcombe Hill, Blackheath, 5 London, England, have invented new and useful Improvements in Pumps, of which the following is a specification.

The object of this invention is to provide a pump by means of which pneumatic tires, 10 and other inflatable articles can be readily inflated to a high pressure.

The invention relates to an improved construction of double action pump having two pistons or plungers which are rigidly connected together and reciprocate in cylinders connected to a common outlet in such a manner that when the pump is actuated a substantially continuous supply of air is forced through the said outlet.

20 A pump constructed according to this invention comprises a pair of coaxial cylinders, a pair of pistons one in each cylinder and rigidly connected together, a segment whose circumference touches or is near to the axis of the cylinders, the said segment being capable of rocking about its centre, and a flexible cable or the like connecting each piston to the segment.

In one way of carrying out my invention 30 the cylinders are formed from a single tube having in it a slot to receive a segment to which a hand lever can be attached. In the cylinders are pistons which are rigidly connected together by a rod or tube and to each piston is connected a flexible cable, which bears against the curved face of the segment and is anchored to the segment preferably in such a manner that its effective length can be adjusted. Each end of the cylinder is closed by a plug against which a washer of compressible material is compressed by a plate, the adjoining circumferential edges of the plug and plate being bevelled in such a manner that when they are 45 drawn together by screws or the like the washer is pressed against the inner circumference of the cylinder and the plug so as to form a fluid tight joint. Or alternatively and preferably the plug is replaced by a 50 cap against which a compressible washer is compressed by a ring, the inner adjoining circumferential edges of the cap and ring being similarly bevelled so as to make a fluid tight joint between the cap and the 55 cylinder. Each cap may be conveniently be provided with a T shaped projection which

can be slid into engagement with claws fixed on a plate, one of the caps having a rotatable cam adapted to engage a groove in the plate and lock the cylinder in position. 60 The plates may conveniently be secured either to a base plate, the floor, or to the running board of an automobile.

The segment may conveniently be made in two parts which are connected together at 65 their upper end and are pivotally mounted on a plate which passes between the two parts of the segment and is rigidly secured to the cylinder in any suitable manner, as by welding. Each part of the segment is 70 provided with a boss to receive a screw threaded rod to one end of which the end of a cable connected to a piston is attached, whilst the other end of the rod is provided with a nut by means of which the effective 75 length of the cable can be adjusted. Each part of the segment is also provided with a thickened portion which is cut away or recessed to receive a detachable hand lever which is locked in position by a pin passing 80 through the lever and the segment.

In operation as the segment is rocked to and fro by the hand lever, the pistons are alternately drawn in and as each one is drawn in, the other is pushed back by the rod 85 or tube connecting them.

In the accompanying drawings which illustrate the invention Figure 1 is a section, Figure 2 is a transverse section on the line A—A, Figure 1. Figure 3 is a plan and Figure 4 a detail perspective view.

1 is a tube the ends of which form cylinders in which are pistons 2 connected together by a tube 3; the pistons 2 are provided with the usual cup leathers 4 which are held in position by washers 5 and nuts 6. Secured to the tube 1 is a plate 7 supported and stiffened by transverse plates 8 which are also secured to the tube 1 in any convenient manner as by welding. 9 are segmental plates secured at their upper ends to a distance piece 10 and also to a bush 11 which passes through a hole in the plate 7 and is rotatable therein. The plates 9 pass through a slot in the tube 1 and tube 3 and the circumference thereof comes close to the axis of the tube. Each segmental plate 9 is provided with a boss 12 which is bored to receive a threaded tube 13 to one end of which is secured a flexible cable 14, the other end of the cable being secured in any convenient manner to a gudgeon pin 15 on a fork 16 on a

piston 2. 17 are nuts by means of which the effective length of the cables can be adjusted. Each plate 9 is also provided with a thickened portion 18 which is recessed or cut away 5 to receive the forked ends 19 of a hand lever which is detachably held in position on the segmental plates 9 by a pin 20. Each end of the tube 1 is provided with a cap 21 against the flanged end of which a ring 22 can be 10 drawn by means of bolts 23 so as to compress a flexible washer 24 between the bevelled adjoining inner circumferential edges of the cap and ring in such a manner as to make a fluid tight joint between the cap 21 and the 15 tube 1. On each cap 21 is a boss 25 having a passage leading from the interior of the cylinder 1 to a nonreturn valve 26 and thence to a pipe 27 to one side of a pressure gauge 28 having a common delivery pipe 29. Each 20 cap 21 is also provided with a T shaped projection 30 adapted to engage lugs 31 which are fast with a plate 32 and overhang a slot 33 formed in the plate. One of the caps 21 is provided with a pin 34 on which is rotatably mounted a cam 35 adapted in one position to engage the walls of a groove 36 in the plate 32 so as to prevent longitudinal movement of the cam and consequently the pump.

In operation, when the segment 9 is rocked 30 by the hand lever 19, a pull is exerted on one of the cables 14 and so on one of the pistons 2 which pushes back the other piston 2 by means of the tube 3 towards the end of its cylinder forcing the air therein to the pressure gauge 28.

What I claim is:—

1. In a pump, the combination of a pair of coaxial cylinders, a pair of pistons one in each cylinder, means for closing an end of each cylinder and comprising a washer, a cap and a ring adapted to compress the washer against the cylinder, means for connecting the pistons rigidly together, a rocking segment whose circumference comes close to the axis of the cylinders, flexible means connecting each piston to the segment, and means for rocking the segment.

2. In a pump, the combination of a pair of coaxial cylinders, a pair of pistons one in each cylinder, a T shaped projection on each cylinder, a pair of plates, lugs on the plates adapted to engage the projections, means for connecting the pistons rigidly together, a rocking segment whose circumference comes close to the axis of the cylinders, flexible means connecting each piston to the segment, and means for rocking the segment.

3. In a pump, the combination of a pair of coaxial cylinders, a pair of pistons one in each cylinder, a T shaped projection on each cylinder, a pair of plates, lugs on the plates

adapted to engage the projections, a groove in one of said plates, a cam rotatably mounted on one of the cylinders and adapted to engage the groove, means for connecting the pistons rigidly together, a rocking segment whose circumference comes close to the axis of the cylinders, flexible means connecting each piston to the segment, and means for rocking the segment.

4. In a pump, the combination of a pair of coaxial cylinders, a pair of pistons one in each cylinder, a T shaped projection on each cylinder, a pair of plates, lugs on the plates adapted to engage the projections, means for connecting the pistons rigidly together, a rocking segment whose circumference comes close to the axis of the cylinders, a cable connecting each piston to the segment, means for adjusting the effective length of the cable, and means for rocking the segment.

5. In a pump, the combination of a pair of coaxial cylinders formed from a single tube, a pair of pistons, one in each cylinder, a delivery pipe, a pipe leading from each cylinder and connected to the delivery pipe, means for closing an end of each cylinder and comprising a washer and a cap and a ring adapted to compress the washer against the cylinder, a T shaped projection on each cylinder, a pair of plates, a groove in one of said plates, a cam rotatably mounted on one of the cylinders and adapted to engage the groove, means for connecting the pistons rigidly together, a rocking segment whose circumference comes close to the axis of the tube, a cable connecting each piston to the segment, means for adjusting the effective length of the cable and a detachable hand lever for rocking the segment.

6. In a pump, the combination of a pair of coaxial cylinders, a pair of pistons one in each cylinder, a tube connecting the pistons rigidly together, a delivery pipe, a pipe leading from each cylinder and connected to the delivery pipe, means for closing an end of each cylinder and comprising a washer, and a cap and a ring adapted to compress the washer against the cylinder, a T shaped projection on each cylinder, a pair of plates, a groove in one of said plates, a cam rotatably mounted on one of the cylinders and adapted to engage the groove, a rocking segment whose circumference comes close to the axis of the cylinders, a cable connecting each piston to the segment and a detachable hand lever for rocking the segment.

In testimony that I claim the foregoing as my invention I have signed my name this 17th day of March, 1922.

SIDNEY EALES HALES.
